UNITED STATES PATENT OFFICE

SAMUEL SOKOLOW, OF NEW YORK, N. Y., ASSIGNOR TO ABINGDON ENGINEERING CO., INC., OF NEW YORK, N. Y., A CORPORATION OF NEW YORK

AUTOMATIC DRY-CELL-MAKING MACHINERY

Application filed April 2, 1927. Serial No. 180,432.

In the manufacture of dry-cells for flash lights and the like a bobbin, as it may be called, is first formed consisting of a cylindrical portion of a matrix composition having 5 a rod-like carbon electrode as a core protruding from one end. This bobbin is placed within a cup-shaped zinc electrode, the electrolyte poured in, the mouth of the cup sealed about the electrode and a brass contact cap 10 placed over the protruding end of the core. It is customary to wrap the bobbin with a fabric before its insertion in the cup in order that no particles of the matrix be broken off in the process of insertion which would bridge 15 the cup and bobbin and short-circuit the cell. The manufacture of the bobbin has heretofore been performed principally by hand.

In a copending application by the present applicant filed August 13, 1926, Serial Number 129,098, a machine for the automatic performance of many of the foregoing steps is disclosed. In one embodiment this machine involves a continuous bobbin conveyor along which are disposed, for instance, a tamping 20 device for curling one end of the fabric wrapper and the cord winding about one another to secure the end of the cord, folding devices for the opposite end of the fabric wrapper and smoothing means for the corners of 25 the folded wrapper to merge them into the cylindrical surface of the wrapped bobbin.

The present invention has for its object an improvement in the machine disclosed in the copending application whereby an adhesive, such as paraffin, may be applied to the 30 protruding end of the carbon core in order to prevent particles thereof from being broken off prior to the application of the cap. Accordingly means to apply adhesive to the protruding end of the core are disposed adjacent 40 the bobbin conveyor at one station where the bobbin pauses in its progress through the machine. Preferably, a container of molten paraffin is disposed at that station wherein the 45 projecting corners of the wrapping are ironed down and merged into the cylindrical surface of the bobbin, and a brush or paraffin applicator is provided movable from a point 50 within the paraffin container into contact with

the bobbin by a convenient moving part of the machine, say the tamping mechanism.

This and other objects of the invention and the means for their attainment will be more apparent from the following detailed description taken in connection with the accompanying drawings illustrating a preferred embodiment thereof, in which:

Figure 1 is a view in transverse vertical section showing a fragmentary part of the 60 bobbin wrapping machine provided with the adhesive applying device according to this invention.

Figure 2 is a plan view of the construction shown in Figure 1.

The bobbin electrode, as it may be called, comprising a carbon rod electrode 5 protruding from one end of a cylindrical matrix bobbin 6 of a diameter materially greater than the electrode, is conveyed through the machine 70 by the endless carrier 8, the bobbin resting in a support or saddle 9, and progressing by a step-by-step movement through the machine from one station to the next where the various operations are performed. Upon reaching 75 the station illustrated in Figure 1, the wrapping has been already tied with the cord, the end of the wrapping folded over the end of the bobbin and secured by adhesive, and the opposite end of the fabric tamped by the 80 tamping device 11 about the rod electrode 5. At the station illustrated, a die 10 is provided which takes the form of a roller constantly driven and provided with a friction surface 85 which engages the peripheral surface of the bobbin and causes its rotation within the carrier 9; and the annular cam surface 12 irons down the protruding corners of the wrapper and merges them with the cylindrical surface of the bobbin.

This rotation of the bobbin by the roller 10 is availed of in the step of applying the paraffin to the carbon electrode which forms the subject matter of this invention. Mounted upon the frame 13 on the opposite side of the conveyor 8 from the ironing means 10, 12 is a tank 14 suitably heated and adapted to contain paraffin in a molten condition. An arm 16 is rigidly mounted on a shaft 16 journaled as at 20, 20 on the side of tank 14 109

and is provided at its extremity with a brush 17 or other paraffin applicator, so that rotation of the rock shaft 19 causes the brush 17 on the arm 16 to be raised, at suitable intervals of time, out of the paraffin bath to apply the paraffin to the end of the bobbin with which it contacts, the arm 16 being of sufficient length for this purpose.

The operating mechanism for the arm 16 10 is conveniently illustrated in Figure 2. The end of the shaft 19 opposite to the arm 16 carries rigidly therewith an arm 21 which is suitably connected, as by the link 22, with the lever 23 which operates the tamping 15 mechanism 11 from the cam 25. Thus every time that the tamping mechanism 11 is operated at the preceding station upon a following bobbin, the bobbin electrode at the succeeding station is treated to an application 20 of paraffin.

Various modifications may be made in the form taken by the mechanism as a whole as well as its application and no limitation is intended by the phraseology of the foregoing 25 specification or illustrations in the accompanying drawings except as set forth in the appended claims.

What I claim is:

1. In a machine for wrapping a bobbin 30 electrode having a protruding core, in combination, a horizontal endless conveyor having a step-by-step movement thereby holding a bobbin thereon momentarily stationary at a predetermined point, a roller disposed 35 above the conveyor to contact with the bobbin carried thereby and rotate the same on the conveyor while momentarily stationary, a tank for paraffin, a pivoted lever, a paraffin applicator carried at the end of the lever, and means to swing the lever end into the 40 tank and into contact with the core.

2. In a machine for wrapping a bobbin electrode having a protruding core in combination, a horizontal endless conveyor for the bobbin having a step-by-step movement, 45 thereby holding the bobbin thereon momentarily stationary at a predetermined point, a means to rotate a bobbin on the conveyor while momentarily stationary, a tank for molten paraffin adjacent the bobbin and on the opposite side of the conveyor from the bobbin rotating means, a rock shaft journaled on the tank, an arm carried with the shaft and adapted to dip its end into the 50 paraffin, a paraffin applicator at said arm end, a second arm carried with the rock shaft and a link pivoted at one end to the second arm and at its other end to an actuating means.

In testimony whereof I affix my signature.

SAMUEL SOKOLOW.
